UNITED STATES PATENT OFFICE.

FRANZ GEISSLER, OF DUSSELDORF-OBERKASSEL, GERMANY.

CASTING APPARATUS FOR FIRST QUALITY AND REFINED STEELS.

Application filed March 24, 1927, Serial No. 178,070, and in Germany December 8, 1926.

This invention relates to a casting apparatus for first quality and refined steels. When this casting apparatus is used it is no longer necessary to clean and turn off the cast blocks. The liquid mass poured into a funnel flows from below into the ingot molds through tangential channels, a core being arranged at the point at which the liquid mass enters into the ingot mold so that an eddy is produced in the flow of the liquid mass, all impurities contained in the liquid mass being thus carried up into the head of the block which after solidifying is cut off same as the root.

An embodiment of the invention is shown, by way of example, in the accompanying drawing, in which

Fig. 1 is a longitudinal section on line I—I of Fig. 2.

Fig. 2 is a plan view of Fig. 1.

The casting tube *c* having a funnel shaped orifice *a* and a lining *b* of refractory material is standing above a vertical bore *d* from which channels *e*, displaced the one with regard to the other, extend tangentially and terminate in circular grooves *f* above which the ingot molds *g* stand upon the base plate *h*. In each circular groove *f* a core *i* is arranged. The head *k* of the ingot mold has a lining of refractory material.

When the liquid metal is poured into the funnel-shaped mouth *a* it flows through the bore *d*, channels *e* and grooves *f* into the ingot

molds *g* and gradually rises in the same. As the channels *e* end tangentially in the grooves *f* underneath the ingot molds *g*, a circulating movement is communicated to the liquid mass which, when the mass is rising in the ingot mold, produces an eddy so that all impurities in the mass are thrown up into the top end *k* of the ingot mold. The head of the cast block can be cut off same as the root so that the cast block is perfectly pure and no cleaning or turning off is necessary, much time and material being thus saved.

I claim:—

A casting apparatus for first quality and refined steel comprising in combination, a base plate having a vertical bore at the centre, a pouring tube above said vertical bore, a funnel shaped inlet at the top end of said pouring tube, conical ingot molds on said base plate around said pouring tube, circular grooves in said base plate one under each ingot mold and a channel connecting each circular groove with said vertical bore so that the point at which said channel terminates in said groove is tangential to said ingot mold so that a circulating movement around the core formed underneath each ingot is communicated to the liquid mass and the impurities are carried up to the top end of said ingot mold.

In testimony whereof I affix my signature.

FRANZ GEISSLER.
